SPRING HINGE FOR FOLDABLE AWNING SUPPORTS

Application filed April 2, 1931. Serial No. 527,080.

This invention relates to improvements in awning supports and has reference more particularly to the construction of a spring hinge adapted for use with foldable awning supports.

It is customary to support awnings by means of supports or brackets formed from two hingedly connected members that will fold against the front of the building wall and which can be extended to hold the awning in operative position. In order to secure automatic extension of such foldable brackets or supports, it is necessary to provide the hinge between the two arms of the support with a spring that tends to move the two arms into extended position.

It is the object of this invention to produce a spring hinge that shall be especially well adapted for use with foldable awning supports and which shall be so constructed that the spring can readily be tensioned so as to exert the force necessary and so that the spring can readily be removed and replaced by another if it should break.

The above and other objects that may become apparent as this description proceeds are attained by means of a construction and arrangement of parts that will now be described in detail, and for this purpose reference will be had to the accompanying drawing in which the preferred embodiment of the invention has been illustrated, and in which:

Fig. 1 is a side elevation of a foldable awning support showing the same in extended position;

Fig. 2 is a view similar to that shown in Fig. 1 but to a larger scale and showing the hinge and adjacent portions of the arm, a part being shown in section to better disclose the construction;

Fig. 3 is a view looking in the direction of arrow 3 in Fig. 2;

Fig. 4 is a section taken on line 4-4, Fig. 2;

Fig. 5 is a section taken on line 5-5, Fig. 4;

Fig. 6 is a section taken on line 6-6, Fig. 5; and

Fig. 7 is a view taken on line 7-7, Fig. 1 and shows the shape of the base of the bracket.

In the drawing reference numeral 1 represents the surface of a wall to which a bracket 2 is attached by means of bolts 3. Secured to the bracket is an arm 4, which is formed from two tubular members telescopically connected, the smaller of the two members has been designated by reference numeral 5. Secured to the outer end of member 5 is a hinge member 6. Member 6 has a shank portion 7 that extends into the end of the arm 5 and is connected to the latter by means of rivets 8. That part of the hinge member that projects beyond the arm is provided with a central opening 9. Lugs 10 extend from one side of the upper and lower parts of the hinge member and these lugs are perforated for the reception of a pivot pin or bolt 11. The end of the hinge member has a projecting portion 12 that is perforated for the reception of a screw 13 that is held in adjusted position by means of a lock nut 14 and which serves as a stop. Reference will be made hereinafter to this stop and the function that it performs. The other arm 15 of the support has a hinge member 16 secured to it. This hinge member has a shank 17 that extends into the arm and is held in place by means of rivets 18. The end of the second hinge member is provided with fingers 19 that overlap the lugs 10 in the manner shown in Fig. 2. The fingers 19 may either be located between the lugs 10 as shown in the drawings, or, on the outside of the lugs as may be considered to be most desirable. The fingers 19 are provided with openings for the reception of the pivot pin 11 and when the parts are assembled, hinge members 6 and 16 can rotate with respect to each other about the axis of the pivot pin. Rotatably connected to the pivot pin is a cylindrical sleeve 20 that is provided at one end with an outwardly extending flange 21. This flange has a plurality of notches 22 and radial openings 23. The sleeve is provided with a longitudinally extending groove or slot 24 for the reception of the inwardly bent end 25 of the spiral spring 26. The other end of spring 26 is provided with a hook portion 27 that engages a bolt 28 secured to the hinge member 6, all as shown in Fig. 4. The spring is tensioned by rotating the sleeve and when

100

the proper tension has been given to the spring, the pawl 29, which is connected with the hinge member 16, is moved over into one of the notches 22, and serves to hold the sleeve 5 against rotation. The spring is applied to the members and tensioned so as to produce a force that tends to move the hinge member 16 against the head of the bolts 13, which therefore serves as a stop to limit the relative rotation of the arms in one direction.

Secured to the outer end of the arm 15 is a wooden bar 30, to which the awning is attached. Since this invention relates to the hinge, the operation of this awning support 15 will not be described in detail, as this is not necessary for a proper understanding of the invention.

It will be seen from the above description that the spring hinge that has been shown on 20 the drawing and described above is of a simple and substantial construction and provided with means for adjusting the tension of the spring so as to get the best operation. If the spring breaks it can be very easily 25 replaced, as all that is required is that the pivot pin 11 be removed so that the broken spring can be taken off and a new one put in place. When the tension of the spring is adjusted, a steel bar is inserted in one of the 30 openings 23 and the sleeve rotated. The pawl 29 can be moved about its pivot into and out of engagement with the notches 22 and when the spring has been properly tensioned, it is held in tensioned condition by means of the 35 pawl as above described.

The base 31 of the bracket is provided on 40 its opposite edges with notches 32 through which securing bolts may pass, it is also provided at its top and bottom with projections 45 33 that have perforations 34. When the brackets are fastened to narrow vertical supports, the securing bolts pass through openings 34, but when the support is wide enough to permit it, the securing bolts pass through notches 32.

Having described the invention what is claimed as new is:

1. In an awning support having two arms, a hinge for connecting the arms, said hinge comprising a hinge member connected with one of the arms and provided with two spaced lugs projecting from one side thereof, the lugs having openings for the reception of a pivot pin, a second hinge member 50 connected with the other arm, the last named hinge member having two spaced fingers adapted to project over the lugs, the ends of the fingers having openings for the reception of the pivot pin, a sleeve secured to the pivot pin intermediate the fingers, a spiral spring surrounding the sleeve, means for attaching one end of the spring to the sleeve, means for attaching the other end of the spring to the first mentioned hinge member, the sleeve having one end provided with an outwardly 55 extending flange having notches in its periphery, a latching pawl connected with the second mentioned hinge member and movable into and out of engagement with the notches in the flange, the spring being tensioned to exert a force tending to hold the arms extended and an adjustable stop for limiting the movement of the arms.

second hinge member and for holding it against movement with respect thereto.

2. In an awning support having two arms, a hinge for connecting the arms, said hinge comprising a hinge member connected with one of the arms and provided with two spaced lugs projecting from one side thereof, the lugs having openings for the reception of a pivot pin, a second hinge member 70 connected with the other arm, the last named hinge member having two spaced fingers adapted to project over the lugs, the ends of the fingers having openings for the reception of the pivot pin, a sleeve secured to the pivot pin intermediate the fingers, a spiral spring surrounding the sleeve, means for attaching one end of the spring to the sleeve, means for attaching the other end of the spring to the first mentioned hinge member, the sleeve having one end provided with an outwardly 75 extending flange having notches in its periphery and a latching pawl connected with the second mentioned hinge member and movable into and out of engagement with the notches in the flange.

3. In an awning support having two arms, a hinge for connecting the arms, said hinge comprising a hinge member connected with one of the arms and provided with two spaced lugs projecting from one side thereof, the lugs having openings for the reception of a pivot pin, a second hinge member connected with the other arm, the last named hinge member having two spaced fingers 80 adapted to project over the lugs, the ends of the fingers having openings for the reception of the pivot pin, a sleeve secured to the pivot pin intermediate the fingers, a spiral spring surrounding the sleeve, means for attaching one end of the spring to the sleeve, means for attaching the other end of the spring to the first mentioned hinge member, the sleeve having one end provided with an outwardly 85 extending flange having notches in its periphery, a latching pawl connected with the second mentioned hinge member and movable into and out of engagement with the notches in the flange.

4. In an awning support having two arms, a hinge for connecting the arms, said hinge comprising a hinge member connected with one of the arms and provided with two spaced lugs projecting from one side thereof, the lugs having openings for the reception of a pivot pin, a second hinge member connected with the other arm, the last named hinge member having two spaced fingers 90 adapted to project over the lugs, the ends of the fingers having openings for the reception of the pivot pin, a sleeve secured to the pivot pin intermediate the fingers, a spiral spring surrounding the sleeve, means for attaching one end of the spring to the sleeve, means for attaching the other end of the spring to the first mentioned hinge member, the sleeve having one end provided with an outwardly 95 extending flange having notches in its periphery, a latching pawl connected with the second mentioned hinge member and movable into and out of engagement with the notches in the flange.

5. A hinge for a two-part foldable awning support comprising a hinge member secured to the end of one of the arms, said hinge member having an opening, and two lugs 100 extending from one side thereof, said lugs having openings for the reception of a pivot pin, a second hinge member secured to the other arm, said second hinge member having two spaced fingers adapted to project over the lugs of the other hinge member, the ends of the fingers having openings for the reception of the pivot pin, an adjustable stop carried by the first hinge member and adapted 105 to engage the second hinge member to 110
